UNITED STATES PATENT OFFICE.

WILLIAM J. PAVEK, OF CHICAGO, ILLINOIS.

TUNING ATTACHMENT FOR STRINGED INSTRUMENTS.

Application filed August 10, 1925. Serial No. 49,175.

My invention relates to improvements in tuning attachments for stringed instruments and has for its object the provision of an improved construction of this character for delicately tuning one or more strings of the instrument.

Other objects will appear hereinafter.

The invention consists in the combinations and arrangements of parts hereinafter described and claimed.

The invention will be best understood by reference to the accompanying drawings, forming a part of this specification, and in which,

Fig. 1 is a top plan view of the head and neck portion of a violin equipped with an attachment embodying my invention;

Fig. 2 is a side view of the same shown partially in section;

Fig. 3 an enlarged detail section taken substantially on line 3—3 of Fig. 2;

Fig. 4 is a view illustrating a modified form of construction.

Fig. 5 is a view illustrating another form of construction.

Fig. 6 is a sectional view of another modified form of my invention.

Fig. 7 is an enlarged cross sectional view taken on line 7—7 of Fig. 6, and

Fig. 8 is a plan view of the bracket or plate included in my attachment.

The form of construction illustrated in Figs. 1, 2 and 3 of the drawing comprises a metal plate 6 arranged to fit within the recess 7 in the head 8 of a violin. The plate 6 is provided with two spring clips 9 arranged to engage over and clamp the upper edge of the side 10 of the head 8. The plate 6 is also provided with a stop lug 11 arranged to rest against the inner end 12 of the recess 7 so as to render the mounting of the plate 6 firm on the head 8. Plate 6 is provided with two inwardly turned perforated lugs or ears 13 in which is mounted an adjusting screw 14 threaded in a block 15 slidable on plate 6. Block 15 is provided with a notch 16 adapted and arranged to engage the E-string 17 of the violin.

By this arrangement the attachment may be readily attached to the head of a violin in position to facilitate the engagement with the E-string of the violin. By adjusting the block 15 upwardly by means of the screw 14 the string 17 will be deflected as indicated by the dotted lines thus varying the tension and consequently effecting delicate

tuning of said string. In actual use the strings of the instrument are tuned in the usual way by means of the tuning pins 18. As is well known it is difficult to thus obtain delicate tuning of the E-string of the violin but by means of the attachment specified and operated as indicated very delicate tuning of the E-string may be accomplished.

In the modified form of construction illustrated in Fig. 4 the plate 6' has stop lug 11 omitted therefrom and said plate is provided with a perforated extension 19 adapted and arranged to engage the tuning pin 18 for the E-string of the instrument and whereby a very secure and more permanent mounting will be afforded plate 6'. Otherwise the construction and operation of the attachment is the same as that already described, and includes the spring clips 9' and the perforated lugs 13' with the adjusting screw therein.

In the modification illustrated in Fig. 5 the plate 6'' is provided with a depending arm 20 having a sharpened point 21 adapted to be pressed into the bottom of the head 8 thus affording a secure and rigid mounting for the plate on the violin head. This form is otherwise also constructed similar to the preceding forms, including clips 9'', lugs 13'', etc.

In Figs. 6, 7 and 8 a further modified form of construction is illustrated, which form includes the plate or bracket 22 provided with a spring clip 22' arranged to engage over and clamp the upper edge of the side 10 of the head 8. This plate 22 is also provided with 2 inwardly turned perforated ears or lugs 23 in which an adjusting screw 24 is rotatably mounted, and threaded in a block 25, which is slidably movable along plate 22. Said block is provided with a notch 26 at its lower side arranged to receive the E-string 17 of the violin. The screw 24 has a reduced neck 27 and a bevelled head 28 formed thereon, said neck being placeable in the slot 29 provided in the lower lug 23, and the bevelled part of said head being seated in a chamfered or notched portion 30 at the inner end of said slot, thereby permitting the head 28 to be conveniently sprung into position in said notched portion 30 and also to be readily removable therefrom by slightly flexing the lower lug 23 and withdrawing the screw 24 through the upper lug.

In this latter modified form of construc-

tion the adjusting screw is placed close to the key which controls the string, considerably closer than in the preceding forms thereby producing a greater effect on the 5 string, that is a greater tuning range than with the preceding forms. In this form the screw is also placed closer to the main or vertical part of the plate 22, and the notch 26 is placed on the outward side of the screw, 10 thereby making it more convenient to mount the attachment on the violin and to place the string into the notch 26. In this form, furthermore the string is pressed downward by the block 25, into the position indicated 15 by the dot and dash line in Fig. 6, instead of drawing the string upwardly, as in the preceding forms, thereby preventing the device, and especially the top of the screw from protruding to any extent upwardly 20 above the upper edge of the side 10 of the violin.

While I have illustrated and described the preferred form of construction for carrying my invention into effect, this is capable of variation and modification without departing from the spirit of the invention. 25 I, therefore, do not wish to be limited to the precise details of construction set forth, but desire to avail myself of such variations and modifications as come within the scope of 30 the appended claims.

Having described my invention, what I claim as new and desire to secure by Letters Patent is:

35 1. A tuning attachment for stringed in-

struments comprising a plate having means thereon for securing the same to the head of a violin or the like; an adjusting screw on said plate parallel to one face thereof; and a block threaded on said screw and sliding 40 against the adjacent face of said plate, said block being adapted and arranged to engage a string of a violin or the like, substantially as described.

2. An attachment for stringed instruments comprising a plate provided at its top with downwardly turned spring lugs adapted to engage over the upper edge of the side of the head of a violin or the like; inwardly turned lugs at the top and bottom 50 of said plate; an adjusting screw rotatably mounted in said inwardly turned lugs; and a block threaded on said screw and sliding against the adjacent side of said plate, substantially as described. 55

3. A tuning attachment for stringed instruments comprising a plate having means thereon for securing the same to the head of a violin or the like; an adjusting screw on said plate parallel to one face thereof; and a block threaded on said screw and sliding 60 against the adjacent face of said plate, said block being adapted and arranged to engage a string of the violin or the like, said block being provided in its top with a notch for engagement with a string of the instrument, substantially as described.

In testimony whereof I have signed my name to this specification.

WILLIAM J. PAVEK.
